UNITED STATES PATENT OFFICE.

ROBERT C. MATHEIS, OF NEW YORK, N. Y., ASSIGNOR TO WESTERN ELECTRIC COMPANY, INCORPORATED, OF NEW YORK, N. Y., A CORPORATION OF NEW YORK.

CORRECTION FOR LINE DISTORTION.

Application filed August 24, 1920. Serial No. 405,780.

The present invention relates to transmission systems over which currents of a range of frequencies are transmitted, and more particularly to certain provisions for 5 securing a more uniform transmission of the currents of the different frequencies.

The invention is adapted specifically for use in multiplex carrier current systems where a comparatively wide range of frequencies is transmitted, but it is also suited to 10 telephone lines or to any system in which it is desired to secure substantially uniform transmission of both low and high frequency currents. It is well known that the 15 attenuation of a line conductor varies with the frequency, the currents of high frequency suffering a greater loss by attenuation than the currents of lower frequency. A common instance of this effect is the distortion 20 which occurs on relatively long telephone lines. The higher harmonics of the voice may be suppressed to such an extent that the voice is unintelligible at the receiver. The greater the range of frequencies used, 25 the more pronounced is the distortion. In multiplex signaling lines, employing high frequency waves as carriers, the range of frequencies may be many times as great as the range represented in a speech wave. It 30 is the particular object of the invention to provide for equalizing for the variable line attenuation for any desired range of frequencies, but especially for the relatively 35 large range of frequencies employed in high frequency multiplex systems.

The exact nature and objects of the invention will be clear from the following detailed description in connection with the accompanying drawing of which Fig. 1 40 represents a schematic circuit diagram of a portion of a repeater circuit embodying the invention, and Fig. 2 shows curves which will be referred to in the description.

The line sections LW and LE terminate 45 at the repeater station in the balancing networks N_1 and N_2 , respectively, in accordance with the usual practice, for enabling currents to be derived from and impressed upon the line sections simultaneously without mutual interference. These line sections 50 may be adapted for transmitting either telephone currents or other currents comprising a range of frequencies, but it will be assumed in the present instance that they 55 are multiplex lines employing a range of

high frequency currents as carriers, which currents are modulated or otherwise controlled in accordance with signals to be transmitted. The lines are shown as associated through a repeater RE for repeating all of the currents on the line LW into the line LE. It is understood that a duplicate repeater circuit might and ordinarily would be employed for repeating in the opposite direction, in which case it would 60 be connected between the taps 24 and 25, but it is deemed sufficient for the purpose of describing the invention to show merely the one repeater.

This repeater is shown as comprising 70 two amplifying stages, the first consisting of the two thermionic discharge devices 1 and 2 connected in balanced relation as to each other, and the second comprising the discharge devices 3 and 4 similarly connected as to each other. These pairs of discharge devices are connected in tandem. The particular object of employing balanced connections of the amplifier tubes in each stage is to secure a substantially linear 75 characteristic, i. e. a constant amplifying factor for all impressed electromotive forces, so that currents of a large number of frequencies can be amplified at the same time without producing modulation between the 80 separate frequency currents. This type of connection has been found in practice to give substantially pure repetition of a complex wave involving a number of frequencies. However, for some purposes one 85 amplifier tube in each of the two stages may be sufficient, and in other cases one stage of amplification may be sufficient. The discharge devices are preferably of the well known type comprising an evacuated 90 tube in which are a heated cathode, a plate and a grid. The grids of the tubes 1 and 2 are connected to the potentiometers 5 and 6, and by means of the sliding contacts, the voltages impressed on the tubes may be 95 varied. These potentiometers are connected across secondary coils 7, the primary 8 of which is bridged across the line LW. Space current for the amplifiers 1 and 2 is supplied from the source 9 through the 100 choke coils 10 and 11, respectively. The current wave components in the output of the amplifiers 1 and 2 pass through the 105 large blocking condensers 12 and 13 and are impressed upon the grids of the respective 110

second stage amplifiers 3 and 4. The output of these amplifiers is through the primary coils 14, which serve to conduct both the space current from the source 9 for these amplifiers and the variation current components. These latter components are transmitted to the secondary coils 15 which are in circuit with the repeating coils 16 inductively related to the line coils of 10 the line section LE.

The connections that have been thus far described, including the amplifier tubes with their necessary input and output connections, if used alone, would repeat all of 15 the currents from the line LW into the line LE substantially in the form in which they are received from the line LW, but with increased amplitude. It is assumed that the currents of the higher frequencies have become more highly attenuated in transmission 20 over the line section LW than currents of the lower frequencies, and also that similar attenuation will be produced by the line section LE. It is desirable, therefore, that at some point on the line means shall be introduced for correcting or equalizing for the 25 variable line attenuation. This correcting means might be introduced at any convenient point on the line, but it is preferably 30 associated with the repeating circuit and is so illustrated in the present instance.

This correcting or equalizing means will be termed herein "an attenuation equalizer" 35 and it may consist broadly of any suitable devices or circuit elements so proportioned in their parts and so related to the line as to exert on the currents transmitted over the line, an effect opposite to that produced by the unequal line attenuation for the different 40 frequencies and to such an extent that the arrival currents are substantially undistorted notwithstanding the line attenuation.

According to the present invention the attenuation equalizer consists of a network including resistance, inductance and capacity 45 and is connected in shunt relation to the line. This network is preferably placed between the two amplifier stages, if a two-stage repeater is employed. By including 50 the discharge devices, such as 1 and 2, between the line and the complex network, reflection losses and impedance reactions between the line LW and the equalizing network are avoided. In the preferred form, 55 the network comprises a resistance 17 in series with a circuit including a condenser 18 and an inductance 19, the whole combination being connected across the line between the amplifiers 1 and 3. In the absence of 60 tubes 2 and 4, this network would be sufficient. Where a balanced amplifier is used, as in the present instance, this network is duplicated on the opposite side by the resistance 20 and the antiresonant circuit comprising capacity 21 and inductance 22. For 65

fixing the normal potential of the grids of the second stage amplifiers 3 and 4, the battery 23 may be included between the filaments and the respective networks as shown.

It is well known that an antiresonant circuit such as 18, 19 offers practically an infinite impedance to transmission through the circuit of currents of the frequency to which it is resonant, and the impedance increases more or less gradually as the resonant frequency is approached. This is illustrated in Fig. 2 in which the curve AB represents for a limited frequency range the relation between the impedance Z, offered by a circuit of this type, and the frequency F of currents transmitted through the circuit. The resonant frequency at which substantially infinite impedance would be offered by the circuit would lie at some distance to the right of the curve shown in this figure. It is seen that as this resonant frequency is approached, the impedance increases. The shape of this impedance curve may be controlled and thus the form of correction may be controlled to a large extent by proper choice of condenser 18, inductance 19, and resistance 17. The function of the resistance 17 is mainly to flatten the impedance curve and to make the variation of impedance less rapid as the frequency increases. The curve 90 AB represents conditions when the resistance 17 is small, and the curve CD represents the case when the resistance 17 is large. By controlling the amount of resistance in 95 series with the antiresonant circuit, therefore, the rate at which the currents of the lower frequencies are shunted across the repeater in excess of the currents of the higher frequencies may be controlled, and the amount of distortion produced by the repeater in the currents transmitted through it may be regulated. Since the impedance 100 of the correcting network in shunt relation to the line is higher for the high frequencies, these will be transmitted through the repeater with greater efficiency than currents of the low frequencies, and the distortion 105 which the repeater introduces is therefore seen to be opposite in sense to the distortion produced by the line attenuation. If the resonant point of the circuits 18, 19 or 21, 22 were chosen to lie within the range of frequencies to be repeated, the impedance of 110 the network with increasing frequency 115 would reach a maximum and then diminish producing an effect opposite to that desired. According to the invention, the circuit 18, 19, and the circuit 21, 22 are each made resonant to a frequency equal to or above any 120 of the frequencies to be repeated, and the portion of the curves AB, CD, etc., are chosen which will give the desired kind of distortion in each case. By way of example 125 it may be stated that in a carrier telephone repeater in which carrier frequencies from 130

5000 to 25000 cycles were used, the resistances 17 and 20 each had a value of about 1500 ohms, the inductances 19 and 22 were each of about 37 millihenrys and the shunt

5 capacity of the coils was found sufficient so that no physical condenser 18 or 21 was necessary. The resonant frequency of this combination proved to be about 26000 cycles, which was the frequency most efficiently 10 transmitted. In another instance, where the maximum gain was to be at a frequency of 10,000 cycles, the resistances had the value of 3500 ohms each, the inductance 150 millihenrys, and the condenser .001 microfarads. These values are given by way of illustration only and are not to be construed 15 as in any way limiting the invention.

It should be understood that the invention is not to be construed as limited to the particular circuit arrangement that has been 20 illustrated and described, but only by the scope of the appended claims.

What is claimed is:

1. In a multiplex carrier wave signaling 25 system, a line having provision for transmitting thereover a series of carrier waves of respectively different frequencies, the attenuation of said line being greater for the higher frequency waves than for the lower, 30 a unidirectionally transmitting amplifier associated with said line for amplifying all of said carrier waves, and a common means also associated with said line for compensating for the unequal attenuation of said 35 waves of the different frequencies, said amplifier being connected between said line and said means.

2. In combination, a line having increasing attenuation with increasing frequency 40 of the currents transmitted thereover, and an attenuation equalizer associated with the line comprising a circuit in shunt of said line including an anti-resonant circuit, the effective shunt impedance of which, as to 45 said line, increases with the frequency of the transmitted currents and a resistance in series with said anti-resonant circuit for modifying the rate of increase of the impedance of the shunt circuit with increasing 50 frequency.

3. A transmission system including two line sections over which electrical waves are being transmitted, a circuit including unidirectionally conducting devices connected 55 in tandem and interconnecting said line sections, and a network included in said circuit between said devices for controlling the attenuation characteristics of said system, said network comprising circuit elements proportioned as a whole to give gradually varying attenuation over the frequency range of the transmitted currents.

4. A transmission system including two line sections, a circuit including unidirectionally conducting repeater elements con-

nected in tandem interconnecting said line sections, and an attenuation equalizer included in said repeater circuit between said repeater elements.

5. In a signaling system, a line divided 70 into two line sections terminating in a repeating station, a repeater for transmitting currents of different frequencies between said line sections comprising a two-stage amplifier and an attenuating network 75 between said stages connected in shunt across said repeater circuit, said network comprising elements proportioned to give a gradually changing attenuation over the frequency range of the currents transmitted 80 over said line, to correct for the unequal attenuation of said currents by said line.

6. A repeater comprising a pair of thermionic discharge devices connected in balanced relation with each other, a second 85 pair of thermionic discharge devices connected in balanced relation with each other, and in tandem as to said first pair, and a circuit bridged across the connection between said pairs of devices including a circuit antiresonant to a frequency outside the 90 range of frequencies of the currents to be transmitted by said repeater and a resistance in series with said antiresonant circuit.

7. In a transmission system, a transmission line the attenuation of which varies with the frequency, a repeating system associated with said transmission line and comprising an impedance, said repeating system including two amplifying transmission paths, one for transmitting in one direction and the other for transmitting in the opposite direction, and an auxiliary circuit whose attenuation varies with the frequency in a manner complementary to that of the line, said auxiliary circuit being included in one of the transmission paths of the repeater system and being associated with the line only through said impedance. 95

8. A transmission system including two line sections over which electromagnetic waves are being transmitted, means for terminating one of said line sections in an impedance approximately equal to the impedance of the line section itself, a bridge 110 across said line section including the input circuit of a vacuum bulb amplifier, means associated with the output circuit of said amplifier for causing different frequency components of said waves to be transmitted with different efficiencies, and a second amplifier having its input circuit associated with said last mentioned means and its output circuit associated with the other of said line sections. 115

In witness whereof, I hereunto subscribe my name this 10th day of August, A. D. 120 1920.

ROBERT C. MATHEWS.
